JOSEPH BASILE, OF NEW YORK, N. Y., ASSIGNOR TO GREENPOINT METALLIC BED COMPANY, A FIRM OF BROOKLYN, NEW YORK, COMPOSED OF DAVID FRANK AND WILLIAM LIES, OF BROOKLYN, NEW YORK, AND JOHN TROUNSTINE, OF NEW YORK, N. Y.

FOLDING BED.

1,278,568.

Specification of Letters Patent. Patented Sept. 10, 1918.

Application filed October 30, 1915. Serial No. 58,766.

To all whom it may concern:

Be it known that I, JOSEPH BASILE, a subject of the King of Italy, and a resident of New York city, in the county of New York and State of New York, have invented certain new and useful Improvements in Folding Beds, of which the following is a specification.

The invention pertains more particularly to metal beds or cribs for the use of babies or small children, and the object of the invention is to produce a bed or crib of the character referred to having hinged side frames and sectional folding end frames, 15 with accessory parts, adapting the entire structure to be very compactly folded so as to occupy the minimum amount of space when not in use.

A further purpose of the invention is to so construct and arrange the several parts of the bed in their relation to each other that the bed may be very conveniently unfolded to a normal operative condition and have its parts, when in such condition, 20 securely held against any accidental occurrence which might otherwise tend to permit the bed sections to move to their folded condition. In the folding of the parts of the bed the two side frames fold over upon the spring or upon the mattress, if the same is on the spring, and the head and foot frames fold toward each other with the lower sections thereof passing below the spring and the upper sections thereof above 25 the spring and upon the folded side frames, thus producing a compact structure occupying but little space and convenient of packing and transportation.

The invention made the subject of this 40 application embodies further improvements on the folding bed or crib made the subject of my application for Letters Patent filed March 1, 1915, Serial No. 11,151, the present improvements pertaining more particularly to certain novel features hereinafter 45 described having to do with the vertically slidable side frame and coöperating parts, and the said invention will be fully understood from the detailed description herein- 50 after presented, reference being had to the accompanying drawings, in which:

Figure 1 is a side elevation of a crib constructed in accordance with and embodying the invention, the parts of the crib being

shown by solid lines in their unfolded relation placing the crib in condition for use, and the lowered position of the slidable side frame being indicated by dotted lines;

Fig. 2 is a like view of the same with the parts of the crib shown in a partly folded condition, the side frames having been folded downwardly toward the spring and the end frames being shown as having their sections partly folded toward opposite sides of the spring;

Fig. 3 is a corresponding view of the same showing the crib in its completely folded position, the usual mattress being omitted;

Fig. 4 is a vertical transverse section of 70 the crib taken on the dotted line 4—4 of Fig. 1;

Fig. 5 is a corresponding section, but showing the side frame in its lower position;

Fig. 6 is a horizontal section through one 75 corner portion of the crib taken on the dotted line 6—6 of Fig. 7;

Fig. 7 is a vertical section, partly broken away, through the corresponding corner portion of the crib taken on the dotted line 80 7—7 of Fig. 6, and

Fig. 8 is a transverse section through a portion of the crib and is presented to illustrate the position of the tubular sleeves through which the vertical end rods of the 85 side frame extend when said side frame is in its folded position.

In the drawings, 10 designates a rectangular angle iron frame of rigid character and constituting the side rails 11 and end 90 rails 12, the latter receiving the customary spring 13 of any suitable type upon which a mattress, not shown, may be supported. The side frames of the bed are designated by the numeral 14 and the end frames by the 95 numeral 15, the side frames comprising upper and lower rods 16, 17 and vertical connecting rods 18, the ends of the rod 16 of each side frame being bent downwardly to form hooks 19, as shown in Fig. 1, and the ends of the rod 17 of each side frame terminating adjacent to the end vertical rods 18. The end vertical rods 18 extend through reasonably short sleeves or tubes 20 and said end rods 18 below said sleeves 20 extend 100 through collars 21 which are pivotally secured, as at 22, to the vertical angle iron bars 23 secured to the side rails 11 of the 105

frame 10. The side frames 14 by reason of the collars 21 become hinged to the general bed structure and are rendered capable of being folded toward and upon one another 5 over the spring 13 and also of being slid vertically from the lower position thereof indicated by dotted lines in Fig. 1 to their upper operative position shown by solid lines in Fig. 1 and then when necessary back 10 to the lower position illustrated by dotted lines. The end rods 18 are capable of sliding through the sleeves or tubes 20 and collars 21, and hence during their vertical movements do not strain or interfere with 15 said sleeves or collars, but on the contrary are guided and controlled thereby. The collars 21 serve as stops for the ends of the rod 17 on the upward movement of the side frames 14 and thereby limit such upward 20 movement, and the upper ends of the sleeves or tubes 20 serve on being engaged by the rods 16 to limit the downward movement or descent of the side frames 14 when the latter are released at the hooks 19 to slide 25 downwardly to their lower position. In my aforesaid application the side frames of the crib may have a hinged movement, but are incapable of being slid downwardly to the position illustrated in Fig. 1 by dotted lines 30 for the purpose of enabling a nurse to conveniently reach an infant occupant of the bed. The hooks 19 formed on the ends of the upper rod 16 of each side frame are adapted to enter apertured ears 24 fastened 35 to those portions of the end frames 15 which may be called the corner posts. When the sides 14 are folded upwardly and outwardly to their vertical position shown in Fig. 1 by solid lines, the said frames may 40 be elevated sufficiently to enable the hooks 19 to be placed over the ears 24 and moved downwardly through the apertures in said ears, thereby securing the side frames in vertical operative position. When the side 45 frames have been turned upwardly and the hooks 19 passed downwardly through the ears 24, I secure the side frames against vertical movement, such as a vigorous child might possibly be able to give to them, 50 by means of wire hooks 25 swiveled upon the lower rod 17 of each side frame and adapted at its lower end to be caught under the lower edge of the side rail member 11 of the frame 10. The hook 25 may be made 55 from a rod of wire doubled upon itself and straddling one of the rods 18, as shown in Fig. 1, this construction and arrangement of the hook keeping the latter in fixed position on the rods 17. When it is desired to 60 fold the side frame 14 downwardly upon the mattress or spring, the hook 25 will be disengaged from the side member and the frame 14 then elevated upwardly until the hooks 19 leave the apertured ears 24, where- 65 upon the side 14 may be folded down-

wardly without obstruction, and the same steps will be performed as to the release of the side frame 14 when it is desired to allow said frame to slide downwardly to its lower position, shown by dotted lines in Fig. 1. 70 The hooks 25 hold the side frames 14, when said frames are in their operative position downwardly to such an extent that said frames 14 cannot be elevated to release the hooks 19 from the ears 24, but when the 75 hooks 25 are disengaged from the side rail members 11, there is sufficient freedom between the ends of the rods 17 and the hinged collars 21 to permit the side frames 14 to be elevated to a sufficient extent to retract the 80 hooks 19 from the ears 24, thus releasing the side frames to be folded inwardly and downwardly or lowered vertically at will. The hinged collars 21 and sleeves or tubes 20 are novel features pertaining to the present application and permit not only of the side frames being folded downwardly and inwardly over the mattress or spring, but also of having a vertical movement. 85

On what may be termed the corner posts 90 of the end frames 15 are rigidly secured plates or lugs 26, which are so disposed that when the side frames 14 are in their lower position the ends of the upper side frame rods 16 are in line therewith and at the outer 95 side thereof, as shown in Fig. 4. The lugs or plates 26 prevent the upper portion of the side frames from being pressed inwardly,—a result which might injure a child lying upon the bed or the shins of a nurse or other person standing at or leaning over the side of the bed or crib. Any outward pressure against the upper portion of a side frame 14 when said frame is in its lower position will be resisted by the contact of the vertical 100 rods 18 against the side rail member 11 of the frame 10, and thus the side rail members 11 and lugs or plates 26 coöperate with each other to prevent objectionable swinging 105 movement of the side frames 14. 110

The end frames 15 correspond with each other and each comprises an upper section 27 and a lower or leg section 28, the upper sections 27 of said end frames constituting head and foot frames and being of any suitable design. The sections 27, 28 are respectively provided adjacent to their meeting portions, at the joint 29, with inwardly extending plates 30, 31, which are pivotally connected together at their inner ends by a 115 pin or pivot 32 to form a hinge. The plates 30, 31 may be regarded as the leaves of a hinge in edge to edge relation to each other and 32 as the pintle of the hinge. The plates 30, 31 are rigid with the sections 27, 28 and 120 the plates 31 are secured by pivots 33 to the ends of the side members 11 of the frame 10. The plates 30 have pivotally secured to them, as at 34, the outer ends of the links 35 whose inner ends are secured by pivots or pins 36 125 130

to the vertical angle bars or posts 23, and when the parts of the crib are in their unfolded operative position, the outer ends of the links 35 are slightly below the inner ends 5 of said links, this having a tendency to aid in holding the end frames of the bed in their upright position during the time that the sides 14 are being positioned. When the upper sections 27 of the end frames are folded 10 toward each other and upon the then folded sides 14, the outer ends of the links 35 ride upwardly above the horizontal plane of the pivots 36, as shown in Figs. 2 and 3, said links during a portion of the inwardly closing 15 movement of the sections 27 moving upwardly at their outer ends and then during the final closing movement of said sections 27 turning downwardly to some extent, as will be understood by a comparative reference 20 to Figs. 2 and 3.

The plates 30, 31 extend inwardly with their adjacent edges in horizontal alinement and in engagement with each other when the crib is in unfolded condition for use, as 25 shown in Fig. 1, the joint between the leaves or plates 30, 31 being in line with the joint 29 or abutting ends of the frame sections 27, 28, and when the parts of the crib are in folded position, as shown in Fig. 3, those edges 30 of the plates 30, 31 which formerly abutted, stand in vertical alinement.

The legs 28 at each end of the bed are mounted on swiveled casters 37, and said legs at each end of the bed or crib are connected 35 by a transverse bar 38, to which casters 39 are secured, the casters 39 being suitably above the lower ends of the legs and adapted when the legs are folded under the frame 10 to engage the floor, as shown in Figs. 2 and 40 3, and finally support the folded crib or bed. The casters 39 serve as rollers upon which the crib after having been folded may be rolled under a bed or across the room or elsewhere. The casters 39 also aid the attendant in moving the bed to its unfolded 45 position, said casters rolling on the floor until about the time that the casters 37 may, during such unfolding operation, engage the floor. The casters 39 are preferably somewhat larger in diameter than the casters 37.

In Fig. 1 I illustrate the crib in unfolded position for use and with the vertically movable side frame 14 secured in its upper position. When it is desired that a child upon 50 the crib may be reached by a nurse or other person, the side frame 14 may be slid downwardly to the position in which it is shown by dotted lines in Fig. 1, thus exposing the interior of the crib. When it is desired to 55 permit the side frame 14 to take its lower position, the attendant will free the hook 25 from the side rail 11 and then sufficiently elevate the side frame 14 to free the hooks 19 from the ears 24, and thereupon the side 60 frame may be allowed to lower, the end rods 65

18 sliding downwardly through the sleeves or tubes 20. I have explained hereinbefore that the side frame 14 when in its lower position is prevented from having a swinging movement by reason of the engagement of 70 the ends of the rods 16 with the ears 26 and the near relation of the lower portions of said frame with the side rail 11 of the frame 10. When it is desired to restore the side frame 14 to operative position, said side 75 frame is simply moved upwardly and the hooks 19 are inserted downwardly through the ears 24 and thereupon the hook 25 is fastened upon the side rail 11.

When it is desired to fold the crib, the 80 first step will be to disengage the hooks 25 from the side rails 11 and then elevate said sides, one after another, to retract the hooks 19 from the ears 24, folding said sides one upon the other downwardly upon the spring 85 13 or the usual mattress if that should be upon the spring, and thereupon the upper ends of the end frames 15 may be forced toward each other, and this will cause the upper sections 27 of said frames to fold downwardly toward each other and upon the then folded sides 14 and the lower sections 28 of said frames 15 to fold toward each other and below the spring 13, as represented in 90 Figs. 2 and 3. When it is desired to unfold 95 the parts of the crib to restore it to condition for use, the attendant may take hold of the then adjacent ends of the frame sections 27 and turn said sections upwardly and outwardly from each other, this having the effect 100 of causing the lower or leg sections 28 to turn downwardly and outwardly from each other until finally said sections 27, 28 reach their vertical position shown in Figs. 1, 4 and 5; thereafter the attendant will disengage the hooks 25 if they have been engaged 105 with the side rails 11, and turn the sides 14 upwardly into vertical position, lifting said sides 14 when in vertical position to engage the hooks 19 with the ears 24. Thereafter 110 the hooks 25 will be connected with the side rails 11.

As means for facilitating the unfolding of the sections of the end frames 15, I preferably provide at each corner of the crib a 115 spring 40 secured at one end to a side rail 11 of the frame 10 and at the other end to the plate 31; the springs 40 are placed under tension or stretched during the folding movement of the members of the end frames 120 15, and hence act during the unfolding movement of said members as power to aid the operator in restoring the crib to condition for use.

What I claim as my invention and desire 125 to secure by Letters-Patent, is:

1. A crib comprising a general spring and mattress supporting frame, end frames, sides, means for permitting one of said sides to slide vertically, and means for securing 130

4. said side in its upper operative position, of said end frames having laterally projecting lugs which serve as side stops for the ends of said upper rod when said side is in its lower position.
5. A crib comprising a general spring and said frame and sleeves pivotally connected with the upper ends of said standards and extending upwardly above the same and freely receiving the end rods of said side and being of sufficient length to be engaged at their upper ends by the upper rod of said side when the side is lowered and to suspend said side in its lower position at a substantial distance above the floor.
10. 2. A crib comprising a general spring and mattress supporting frame, end frames, sides, means for permitting one of said sides to slide vertically, and means for securing said side in its upper operative position, said means for permitting said side to slide vertically comprising standards secured to and projecting above the side of said general frame, collars swiveled to the upper ends of said standards, and sleeves adapted to rest on said collars freely and freely receiving the end rods of said side and being of suitable length to be engaged at their upper ends by the upper rod of said side when the side is lowered and to suspend said side in its lower position above the floor.
15. 3. A crib comprising a general spring and mattress supporting frame, end frames, sides, sides, means for permitting one of said sides to slide vertically, and means for engaging the ends of the upper rod of said side with the corner posts of said end frames, said means for permitting said side to slide vertically comprising standards secured on and projecting above the side of said general frame, collars swiveled to the upper ends of said standards, and sleeves adapted to rest on said collars freely and freely receiving the end rods of said side and being of suitable length to be engaged at their upper ends by the upper rod of said side when the side is lowered and to suspend said side in its lower position above the floor.
20. Signed at Brooklyn, in the county of Kings and State of New York, this 29th day of October, A. D. 1915.
